APPARATUS FOR PRODUCING ANIMATED SHADOWS

Jack J. Levin, Baltimore, Md.

Application October 5, 1934, Serial No. 747,095

20 Claims. (Cl. 40—132)

This invention relates to an apparatus for producing animated shadows.

The effect produced by moving a light in rear of a translucent screen with an opaque object 5 interposed in the path of the light directed upon the screen so as to vary the position of the shadows cast upon the translucent screen by the interposed object has been well known. Attempts have been made to appropriate this idea 10 upon screens by personal hand movement of the light to produce the varying shadow effects and the results were largely dependent upon the ability of the operator to move the light through the same path in successive operations. The results 15 obtained by such methods were unsatisfactory both from the standpoint of difficulty of manipulation and reproduction of the effects and of the limitations in the kinds of effects produced.

Among the objects of this invention is the provision of means whereby a wide variety of novel 20 shadow effects may be produced automatically and in steady and constant sequence for all of the cycles of movements.

A further object of this invention is the provision of means whereby a light is constrained 25 to move repeatedly in a definite path for each cycle of effects.

A still further object of this invention is the provision of means whereby shadow effects may 30 be produced repeatedly on a translucent screen in a given definite sequence of cyclic changes wherein a light is constrained to move repeatedly under cam guidance in a definite path for each cycle of effects.

Other, further and more specific objects of this invention will become readily apparent to persons skilled in the art from a consideration of the following description when taken in conjunction with the accompanying drawings, wherein:

Fig. 1 is a cross-sectional view through the casing containing my new device and showing parts of the apparatus in elevation.

Fig. 2 is a detail side view of a specific embodiment of my invention and showing a cam and link motion connected therewith for directing the path of the light.

Fig. 3 is a fragmental detail view, partly in section, showing the connection of the lamp to the link or arm which bears this light against 50 the cam.

Fig. 4 is a side view, illustrating a different form of cam and a modified form of link motion for directing the light.

Fig. 5 is a fragmental, diagrammatic view 55 showing a construction whereby the light is caused to traverse through an irregular path by means of a moving drag chain.

Fig. 6 is an enlarged cross-section along line 6—6 of Fig. 5, and shows the particular manner 60 in which the lamp socket is supported on the

drag chain and the method of establishing electrical contact.

Fig. 7 is an enlarged, fragmental, sectional view along line 7—7 of Fig. 2 and showing the means for securing in position the arms of the link mechanism of my device after these arms have been adjusted to their proper pivot point for a particular cycle of motion, and also the swivel means associated with the link mechanism.

Referring to Fig. 1, the apparatus comprises 10 the casing 1 provided with a front opening 2 over which is positioned a translucent screen 3 of glass or other suitable material. An electric motor 4 deriving current from a suitable source is secured to the base 5 suitably attached to the 15 casing 1. The rotary movement from this motor is transmitted by means of the worm 6, gear 7, shaft 8, bevel gears 9 and 10 and hollow shaft 11 to the link mechanism 12 carrying the lamp 13. In the form shown in Fig. 2, this link mechanism 20 comprises the adjustable arms or links 14 and 15 and the arm 16 carrying the spring 17. The hub 18 of the arm 14 is attached to the reduced portion 19 of the driving hollow shaft 11 to which it is secured by the bolt 20. The other end of 25 this arm 14 contains the slot 21 in which there is provided the adjusting bolt 22 which engages the nut 23, whereby the position of the pivot of the arm 15 is radially adjusted.

The bolt 22 is provided with a head 24 and 30 also with an enlarged portion 25 which is disposed in the bore 26 of the arm 15. The length of this enlarged portion 25 is greater than the depth of the bore 26, while the diameter of this enlarged portion 25 is greater than the width 35 of the slot 21, so that when the bolt 22 is tightened by the nut 23 it will be held in fixed position to the arm 14 and will serve as a pivot for the arm 15, permitting this arm 15 to rock freely on it.

The arm 16 is held in pivotal relationship by the pin 27 which is disposed in a bore in the arm 15. If desired, the pin 27 may be made adjustable in the arm 16 by providing this arm with a slot instead of a bore for receiving the 45 pin 27 which would then be held secured in any desired position of the slot by an arrangement similar to that illustrated for holding the bolt 22 in slot 21, while allowing the arm 15 to swing on this bolt 22. The arm 16 passes through the eye 28 of the swivel bolt 29 fastened to the arm 14. This swivel bolt 29 also serves as a stop for the spring 17 carried by the arm 16.

The cam 30 is held in fixed position on the solid shaft 31, maintained in stationary position by any suitable means such as a key or pin 31a that also passes through the support for this shaft. As the hollow shaft 11 is turned, it will effect rotation of the arm 14 secured thereto, and this will carry with it the link mecha- 60

nism supported thereby and the lamp 13. The arrangement of arms and spring will cause the lamp to bear against the edge of the cam 39 and the lamp 13 will traverse a path corresponding to the shape of the outer edge of the cam. Although in the illustration shown this cam is approximately heart-shaped, it is to be understood that my invention is not limited in this respect, but cams of other configurations may 5 be used within the scope of my invention. As a further means of maintaining the lamp 13 in proper relationship to the cam 39, a loose collar 32, provided with circumferential flanges 33 is positioned on the stem 34 extending from the 10 lamp 13. This stem 34 is of greater length than the collar 32, so that when the arm 15 is tightened against this stem 34 by operation of the nut 35, the collar 33 will still be free to revolve on the stem 34, and the flanges 33 will provide 15 against axial or longitudinal displacement of the lamp 13 on the cam 39.

The lamp 13 is carried by the arm 15 and electric current is conducted from any convenient supply, such as the transformer 36, by means 20 of the lead 37, brush 38, insulated rotating collar 39 and lead 40 to the lamp 13. The other end of the lamp circuit is grounded to a suitable part of the framework.

Attached to the rear face of the translucent 25 screen 3 are shadow-producing objects 41 and 42. In the object 41 a portion rests directly against the translucent screen while the parts 43 and 44 extend from the translucent screen, so that when the lamp is caused to rotate, the 30 shadow cast by the portion of the object 41 which bears against the translucent screen will be practically constant and stationary, irrespective of the position of the light. However, the shadow cast by the parts 43 and 44 will depend upon 35 the position of the lamp 13 in the path of revolution and will increase or decrease according to the change of the angles at which the rays of the light will be intercepted by these parts of the object. The effects produced are continual 40 changes in the lengths of the shadows, resulting in the production of moving objects. By having the light 13 constrained to move in a fixed path and adjusting the position of the shadow-casting object relative to the translucent screen 45 and the orbit of the moving light, novel animated shadows are produced upon the screen which can be accurately controlled and caused to reproduce with the same sequence of changes in 50 all cycles of revolution of the light.

In the shadow-casting object 42 there are 55 shown a portion resting directly against the translucent screen 3, as well as the parts 45 and 46 (which are very similar to the extending parts 43 and 44 of the object 41) and also the part 60 47 which is an extension of the part 46 and is substantially parallel to but distant from the translucent screen 3. This portion 47 of the object admits of the production of shadows which give quite different effects from those produced 65 by extensions such as 43, 44, 45 and 46. The extent of the variation in the shadow cast by an object such as part 47 interposed in the path of the rays from a lamp moving in a fixed orbit depends upon its distance from the translucent 70 screen 3. The range of variation increases with the amount of spacing, and as this range of variation increases the speed of movement of the changing shadow also increases. Consequently, by adjusting the distance between the object 75 and the screen, shadow movements of the de-

sired speed and range may be obtained by a given movement of the light. Also, by having a combination of objects such as the part 47 disposed at different distances from the screen, some of these shadow objects may be made to move more rapidly and through a greater range than others. This provides a very effective means for showing objects that have some parts moving more rapidly than other moving parts.

In the modification shown in Fig. 4, the arm 10 48 is keyed or otherwise secured to the hollow shaft 11. This arm 48 is provided at one end with the cuff 49 for directing one end of another arm 50 in its reciprocating, sliding movement against the arm 48. At the other end of 15 the arm 48 there is a recess or socket 51 which receives a collar 52 through which the other end 53 of the reciprocating arm 50 passes. Around the end 53 projecting beyond the collar 52 there is provided a coil spring 54 the 20 ends of which bear against the stop 55 and collar 52. The arm 50 is enlarged in the center and is provided with a slot 56 whereby it slides over the hollow shaft 11. When the shaft 11 is revolved, the arm 48 is rotated therewith and 25 this causes the arm 50 to rotate. The spring 54 serves to urge the arm 50 toward the spring end and the lamp 13 carried in the end of the arm 50 is kept in engagement with the cam 57. A roller 58, similar in construction to the loose 30 collar 32 in Fig. 3, is provided, so that the lamp 13 will ride freely over the cam 57. By this construction, the combined rotating and reciprocating motions of the arm 50 will cause the lamp 13 to travel in an orbit corresponding to the 35 configuration of the outer edge of the cam 57.

In the modification shown in Figs. 5 and 6, there are provided the inner and outer cam track guides 59 and 60, respectively, for the roller or collar 61 loosely mounted on the pin 62. The 40 collar 61 is kept from longitudinal displacement on the pin 62 at one side by means of the collar 63 and set screw 64 and at the other side by the washer 65, collar 66 and head 67 on the end of the pin 62. The collar 66 is connected to the sprocket 45 chain 68, which engages the driving sprocket wheel 69 and the idlers 70. The sprocket wheel 69 derives its power through the bevel gears 71 and 72, shaft 73, bevel gears 74 and 75 and shaft 76. As the shaft 76 turns, it will effect rotation 50 of the sprocket wheel 69 which will drive the chain 68 and carry the pin 62 along with it, and the roller 61 will traverse a path between the cam track guides 59 and 60.

By having this collar 61 loosely and rotatably 55 mounted, the mechanism operates more smoothly and local wear of the collar by the edge of the cam against which it bears is considerably reduced. In like manner, local wear of collars 32 and 58 employed with the other forms of cams 60 is also reduced by having these collars loosely and rotatably mounted.

If desired, more than one driving sprocket wheel may be employed. Under such conditions, the driving sprocket wheels could take the place 65 of some of the idlers 70.

Threaded upon or otherwise secured to the pin 62 is a base 76 of insulating material, which supports the lamp socket 77. This insulating base 76 is provided with a pair of bores in which are 70 disposed the threaded caps 78, the springs 79 and a portion of each of the contact bolts 80, the head 81 of each of these bolts being positioned in the enlarged portion 82 of each bore while the other end 83 of each bolt contacts with the tracks 84 75

and 85 in the slots 86 and 87 of the grooved guides 88 and 89, respectively. These guides 88 and 89 are of insulating material and the tracks 84 and 85 serve to bring current to the lamp inserted in the socket 77. The guides 88 and 89 are secured to the cam track guides 59 and 60, and they follow the configuration of the inside edges of these cam track guides. It will be seen by reference to Fig. 6 that each of the bolts 80 5 passes through the smaller portion of the bore in the insulating base 76 and is free to move therein. These bolts serve as brush contacts when the lamp inserted in the socket 77 is carried around by the drag chain 68. The electric circuit is 10 established from the track 84 through one of the bolts 80, through the wall 90 in one of the bores in the base 76, and through the spring 91 to the lamp. The electric circuit extends from the lamp to the socket casing 92, lead 93, wall 94 in the 15 other bore of the insulating base 76, the bolt 80 within this bore and the track 85.

The cam track guides 59 and 60 are fastened to a suitable stationary support 95 and the shafts for the driving sprocket wheel 69 and the idlers 25 70 are also supported in suitable bearings, which, if desired, may be fastened to the support 95.

By regulating the shape of the cams in the 30 constructions shown in Figs. 2, 4 and 5, the orbit of the lamp 43 may be correspondingly regulated to give circular, elliptical, reciprocating and unlimited kinds of regular as well as irregular motions. Also, through the proper selection of 35 cams, the movement of the lamp may be regulated for various relative speeds during any cycle of changes at the proper parts of its orbit, thereby admitting of the production of a wide variety of novel shadow effects.

The preferred materials for the shadow-producing 40 objects are thin opaque sheets of metal, artificial cellulose products, and paper or other fibrous materials capable of retaining the shape into which formed. Thin sheets of copper, brass and aluminum have been found satisfactory.

I have found, however, that by making the 45 shadow-casting objects of translucent or transparent sheets of material and mildly tinting these materials, when a light is passed through such objects to the translucent screen, such objects will intercept the colors other than that with 50 which they are tinted and transmit to the translucent screen the rays of light corresponding to the tint. By having such colored objects positioned as shown in the illustration herein, instead of obtaining black animated objects upon the 55 translucent screen, colored animated objects corresponding to the colored shadow-casting objects will be obtained. By proper selection and distribution of these colors among the shadow-casting objects, very picturesque animated shadows can 60 be produced with my process and apparatus.

Although in general thin sheets openly spaced from the translucent screen are preferred for the shadow-casting objects, it is to be understood 65 that the shadow-casting objects may have the spaces from the screen enclosed or contain solid portions, for it will be readily understood that the determining factor of the shadow-casting object regarding size and movement of the animated shadows is the distance from the translucent screen of the surface exposed to the rays of the light.

I have also found that it is highly desirable to have the surface of the interior of the casing and as well as the surfaces of all parts of the appa- 75

ratus facing the translucent screen (except the lamp 43 and the portion of the shadow-casting object designed for transmission of colored light) of light absorbing material. By coating the interior of the casing and such other parts of the device with a dull black paint, objectionable reflected light will be avoided. 5

For most effective showing of the animated shadows, I have found it desirable to have the bulb and the inner filament small and the light 10 of high intensity. The pencil of rays from this light diverge upon the translucent screen.

In the specific illustrations here shown and described, the adaptation of the cam mechanism for operating the light in connection with the 15 productions of animated shadows has received particular attention. It is to be understood, however, that this novel cam mechanism is not limited to any particular use, but can be appropriated for a wide variety of uses and in numerous other mechanisms and mechanical constructions. In the claims the expression "connection 20 for rotation" as applied to the light is intended to cover movement of the light in cyclic paths or closed circuits of various forms and configurations 25 including cyclic paths of the particular configurations shown in the drawings.

This application is a continuation-in-part of my applications Ser. No. 638,279 and Ser. No. 641,907. 30

The present invention is not limited to the specific details set forth in the foregoing examples which should be construed as illustrative and not by way of limitation, and in view of the numerous modifications which may be effected therein 35 without departing from the spirit and scope of this invention, it is desired that only such limitations be imposed as are indicated in the appended claims. 40

I claim as my invention:

1. In an apparatus for producing animated shadows, a casing, a translucent screen on one side of the casing, an ensemble of elements within said casing, said ensemble comprising a rotatable shaft connected with power driving means 45 and a light having connection for rotation by said shaft, another shaft passing into but not locked with the first shaft, a cam supported by the second shaft, said cam having a guide engaging said ensemble for regulation of change in the radial 50 distance of said light from said shaft during cyclic movement of said light, and an object positioned in the path of the rays issuing from said light upon said screen, said object having the surface exposed to the rays of light distant from 55 the translucent screen.

2. In an apparatus for producing animated shadows, a casing, a translucent screen on one side of the casing, an ensemble of elements within said casing, said ensemble comprising a rotatable shaft connected with power driving means and a light having connection for rotation by said shaft, another shaft passing into but not locked with the first shaft, a cam supported by the second shaft, said cam having a guide engaging said ensemble for regulation of change in the radial distance of said light from said shaft during cyclic movement of said light, and an opaque object positioned in the path of the rays issuing from said light upon said translucent screen, said 65 opaque object having a portion of the surface exposed to the rays of light distant from the translucent screen. 70

3. In an apparatus for producing animated shadows, a casing, a translucent screen on one 75

- side of the casing, an ensemble of elements within said casing, said ensemble comprising a rotatable shaft connected with power driving means and a light having connection for rotation by said shaft, 5 another shaft passing into but not locked with the first shaft, a cam supported by the second shaft, said cam having a stationary guide engaging said ensemble for regulation of change in the radial distance of said light from said shaft during the 10 cyclic movement of said light, and an object positioned in the path of the rays of light issuing from said light upon said translucent screen, said object having a portion partially opaque and with the surface exposed to the rays of light distant 15 from the translucent screen.
4. In an apparatus for producing animated shadows, a casing having the interior surfaced with light absorbing means, a translucent screen on one side of the casing, an ensemble of elements 20 within said casing, said ensemble comprising a rotatable shaft connected with power driving means and a light having connection for rotation by said shaft, another shaft passing into but not locked with the first shaft, a cam supported by 25 the second shaft, said cam having a guide engaging said ensemble for regulation of change in the radial distance of said light from said shaft during cyclic movement of said light, and an opaque object positioned in the path of the rays issuing 30 from said light upon said translucent screen, said opaque object having a portion of the surface exposed to the rays of light distant from the translucent screen.
5. In an apparatus for producing animated 35 shadows, a casing, a translucent screen on one side of the casing, an ensemble of elements within said casing, said ensemble comprising a rotatable shaft connected with power driving means and a light having connection for rotation by said 40 shaft, another shaft passing into but not locked with the first shaft, a cam supported by the second shaft, said cam having a stationary guide engaging said ensemble for regulation of change in the radial distance of said light from said shaft during cyclic movement of said light, and an object positioned in the path of the rays issuing 45 from said light upon said translucent screen, said object having a portion of different transmissibility of light than the rest of said 50 object and having the surface exposed to the rays of light distant from the translucent screen.
6. In an apparatus for producing animated 55 shadows, a casing, a translucent screen on one side of the casing, an ensemble of elements within said casing, said ensemble comprising a rotatable shaft connected with power driving means and a light having connection for rotation by said shaft, another shaft passing into but not locked with the first shaft, a cam supported by the second shaft, said cam having a guide engaging said ensemble for regulation of change in the radial distance of said light from said shaft during cyclic movement of said light, a spring and an arm 60 for maintaining said light in contact with the guiding part of said cam, and an opaque object positioned in the path of the rays issuing from said light upon said translucent screen, said opaque object having a portion of the surface exposed to the rays of light distant from the translucent 65 screen.
7. In an apparatus for producing animated 70 shadows, a casing, a translucent screen on one side of the casing, an ensemble of elements within said casing, said ensemble comprising a rotatable shaft connected with power driving means
- and a light having connection for rotation by said shaft, another shaft passing into but not locked with the first shaft, a cam supported by the second shaft, said cam having a guide engaging said ensemble for regulation of change 5 in the radial distance of said light from said shaft during cyclic movement of said light, a spring and a plurality of arms for maintaining said light in contact with the guiding part of said cam, and an opaque object positioned in the path of the rays issuing from said light upon said translucent screen, said opaque object having a portion of the surface exposed to the rays of light distant 10 from the translucent screen.
8. In an apparatus for producing animated 15 shadows, a casing, a translucent screen on one side of the casing, a light within said casing, means comprising a cam and a drag chain for moving the light in continuous cycles in a fixed path, means for driving said chain, and an opaque object positioned in the path of the rays issuing from said light upon said translucent screen, said opaque object having a portion of the surface exposed to the rays of light distant 20 from the translucent screen.
9. In an apparatus for producing animated 25 shadows, a casing, a translucent screen on one side of the casing, a light within said casing, means comprising a cam on a stationary inner shaft and driving mechanism carrying said light, 30 in engagement with the guide face of said cam and disposed on an outer hollow shaft coaxial with said inner shaft for moving the light in continuous cycles in a fixed path, and an opaque object positioned in the path of the rays issuing from said light upon said translucent screen, said opaque object having a portion of the surface exposed to the rays of light distant 35 from the translucent screen.
10. In an apparatus for producing animated 40 shadows, a casing, a translucent screen on one side of the casing, a light within said casing, means comprising a cam on a stationary inner shaft, an arm fastened on an outer hollow shaft coaxial with said inner shaft and another spring-actuated arm co-operating with the first arm for 45 moving the light in continuous cycles in a fixed path, a roller connected to said light and bearing against said cam, and an opaque object positioned in the path of the rays issuing from said light upon said translucent screen, said opaque object having a portion of the surface exposed to the rays of light distant 50 from the translucent screen.
11. In an apparatus for producing animated 55 shadows, a casing, a translucent screen on one side of the casing, a light within said casing, means for moving the light in continuous cycles in a fixed path, said means comprising co-operating cam track guides, a roller connected to said light and movable in said guides, a drag chain for moving said light and roller, and means for driving said chain, and an opaque object positioned in the path of the rays issuing from said light upon said translucent screen, said opaque 60 object having a portion of the surface exposed to the rays of light distant from the translucent screen.
12. In an apparatus for producing animated 65 shadows, a casing, a translucent screen on one side of the casing, a light within said casing, means for moving the light in continuous cycles in a fixed path, said means comprising stationary co-operating cam track guides, a roller connected to said light and movable in said guides, a drag 70
- 75

chain for moving said light and roller, and means for driving said chain, and an opaque object positioned in the path of the rays issuing from said light upon said translucent screen, said 5 opaque object having a portion of the surface exposed to the rays of light distant from the translucent screen.

13. In an apparatus for producing animated shadows, a casing, a translucent screen on one 10 side of the casing, an ensemble of elements within said casing, said ensemble comprising a rotatable shaft connected with power driving means and a light having connection for rotation by said shaft, another shaft passing into but not 15 locked with the first shaft, a cam supported by the second shaft, said cam having a stationary guide engaging said ensemble for regulation of change in the radial distance of said light from said shaft during cyclic movement of said light, 20 means for supplying electric current to said light from a source which does not move with said light when said light is moving in the cyclic path, and an object positioned in the path of the rays issuing from said light upon said screen, said object 25 having some of the surface exposed to the rays of light distant from the translucent screen.

14. In an apparatus for producing animated shadows, a casing, a translucent screen on one side of the casing, an ensemble of elements within 30 said casing, said ensemble comprising a rotatable shaft connected with power driving means and a light having connection for rotation by said shaft, another shaft passing into but not locked with the first shaft, a cam supported by the second shaft, said cam having a stationary guide 35 engaging said ensemble for regulation of change in the radial distance of said light from said shaft during cyclic movement of said light, means for supplying electric current to said light from 40 a source which does not move with said light when said light is moving in the cyclic path, and an opaque object positioned in the path of the rays issuing from said light upon said translucent screen, said opaque object having a portion of 45 the surface exposed to the rays of light distant from the translucent screen.

15. In an apparatus for producing animated shadows, a casing, a translucent screen on one side of the casing, an ensemble of elements within 50 said casing, said ensemble comprising a rotatable shaft connected with power driving means and a light having connection for rotation by said shaft, another shaft passing into but not locked with the first shaft, a cam supported by the second shaft, 55 said cam having a guide engaging said ensemble for regulation of change in the radial distance of said light from said shaft during cyclic movement of said light, means for supplying electric current to said light from a source which does not move with said light when said light is moving in the cyclic path, and an object positioned in the path of the rays issuing from said light upon said translucent screen, said object having a portion of 60 different transmissibility of light than the rest of said object and having some of the surface exposed to the rays of light distant from the translucent screen.

16. In an apparatus for producing animated shadows, a casing, a translucent screen on one 65 side of the casing, a light within said casing, means comprising a cam and a drag chain for moving the light in continuous cycles in a fixed path, means for driving said chain, means for 70 supplying electric current to said light from a

source which does not move with said light when said light is moving in said fixed path, and an opaque object positioned in the path of the rays issuing from said light upon said translucent screen, said opaque object having a portion of the 5 surface exposed to the rays of light distant from the translucent screen.

17. In an apparatus for producing animated shadows, a casing, a translucent screen on one side of the casing, a light within said casing, 10 means for moving the light in continuous cycles in a fixed path, said means comprising co-operating cam track guides, a roller connected to said light and movable in said guides, a drag chain for moving said light and roller, and means for 15 driving said chain, means for supplying electric current to said light from a source which does not move with said light when said light is moving in said fixed path, and an opaque object positioned 20 in the path of the rays issuing from said light upon said translucent screen, said opaque object having a portion of the surface exposed to the rays of light distant from the translucent screen.

18. In an apparatus for producing animated shadows, a casing, a translucent screen on one side 25 of the casing, an ensemble of elements within said casing, said ensemble comprising a rotatable member connected with power driving means and a light having connection for rotation by said rotatable member, another member within said 30 casing having a guide engaging said ensemble for regulation of change in the distance of said light from the axis of said rotatable member during cyclic movement of said light, and an object positioned in the path of the rays issuing from 35 said light upon said screen, said object having the surface exposed to the rays of light distant from the translucent screen.

19. In an apparatus for producing animated shadows, a casing, a translucent screen on one side of the casing, an ensemble of elements within 40 said casing, said ensemble comprising a rotatable member connected with power driving means and a light having connection for rotation by said rotatable member, another member within said 45 casing having a guide engaging said ensemble for regulation of change in the distance of said light from the axis of said rotatable member during cyclic movement of said light, and an object positioned in the path of the rays issuing from 50 said light upon said translucent screen, said object having a portion of different transmissibility of light than the rest of said object and having some of the surface exposed to the rays of light distant from the translucent screen.

20. In an apparatus for producing animated shadows, a casing, a translucent screen on one side of the casing, an ensemble of elements within 60 said casing, said ensemble comprising a rotatable member connected with power driving means and a light having connection for cyclic movement in a fixed path by said rotatable member, another member within said casing having a guide engaging said ensemble for regulation of 65 change in the distance of said light from the axis of said rotatable member during said cyclic movement of said light, and an object positioned in the path of the rays issuing from said light upon said screen, said object having the surface exposed to the rays of light distant from the translucent screen.
